UNITED STATES PATENT OFFICE.

WILLIAM L. MURPHY, OF SAN FRANCISCO, CALIFORNIA, ASSIGNOR, BY MESNE ASSIGNMENTS, TO MURPHY DOOR BED COMPANY, OF SAN FRANCISCO, CALIFORNIA, A COPARTNERSHIP FIRM CONSISTING OF WILLIAM L. MURPHY AND WILLIAM K. WHITE.

SOFA BED.

Application filed May 20, 1920. Serial No. 382,717.

To all whom it may concern:

Be it known that I, WILLIAM L. MURPHY, a citizen of the United States, and a resident of the city and county of San Francisco, 5 State of California, have invented a new and useful Sofa Bed, of which the following is a specification.

My invention relates to folding beds and particularly to that class of beds which are 10 adapted to be converted into sofas.

An object of my invention is to provide a bed with wire and upholstered mattresses, all of standard size, which is capable of being converted into a sofa by folding.

15 Another object of my invention is to provide a sofa bed in which are included automatically extended legs for supporting the foot end of the unfolded bed. Another object of my invention is the provision of a 20 structure of the character described embodying a relatively high head board which in the sofa form of the device extends across the bottom of the housing structure.

Another object of the invention is to provide 25 a structure of the class described which is unfolded into a standard bed in a single movement.

Another object of the invention is to provide 30 a structure of the class described in which a three-part bed frame is folded into a space not materially longer than the width of the frame.

The invention possesses other features of 35 advantage, some of which, with the foregoing, will be set forth in the following description of the preferred form of my invention which is illustrated in the drawings accompanying and forming part of the specification. It is to be understood that I 40 do not limit myself to the showing made by the said drawings and description, as I may adopt variations of the preferred form within the scope of my invention as set forth in the claims.

45 Referring to the drawings:

Fig. 1 is a plan view of the device of my invention when unfolded into the bed form, a portion being broken away to lessen the width of the figure; and Fig. 2 is a side elevation of the same, showing a mattress on the bed frame. Fig. 3 is a vertical section

through the structure when folded into the sofa form. Figs. 4 and 5 are perspective views of details of the structure.

Broadly, my invention comprises a sofa in 55 which a three-part bed frame is arranged below and behind the seat and back of the sofa in such a way that with a single, easily controlled movement, the bed frame is turned outwardly to extended horizontal 60 position. The manner of arranging the parts permits a standard thickness upholstered mattress to be mounted on the wire fabric spring carried by the bed frame, while retaining a normal size of sofa structure. 65 Preferably the proportions and arrangements are such that the width of the bed structure when extended, is the same as the length of the sofa. This makes it unnecessary to provide a sofa as long as a standard 70 bed and is one of the advantages possessed by my invention.

Referring first to Figs. 2 and 3 a housing structure 2 is provided in which the sofa bed of my invention is arranged. The base of 75 the housing structure comprises a box 3, on each end of which is fixed a frame comprised of the vertical posts 4 and 5 and the link 6 connecting the two posts and extending forwardly of the front post 4. A seat 80 frame 7 provided with a suitably upholstered seat 8 is pivoted to the front ends of the cross links 6 by pivot pins 9. The seat frame 7 is adapted to turn upwardly and outwardly about the pivots 9 to a substantially horizontal inverted position as shown in Fig. 2. A three-part bed frame is provided, comprising a main frame, and foot and head frames. The foot frame 10 is pivoted to the seat frame 7, at each side, the 90 pivots 11 connecting the extension arms 12 fixed on each end of the seat frame to extension arms 13 fixed to the foot frame 10 at opposite sides. Normally as shown in Fig. 3, this frame 10 is in an upright position. 95 Attached by the pivots 14 to the inner or lower end of the frame 10 is the main bed frame 16. The frame 16 is also provided on each side with an extension arm 17, secured by the pivots 18 to the tops of the posts 5. 100 The frame 16 is adapted to turn from its folded position shown in Fig. 3, upwardly

and outwardly about the pivots 18 to an inverted horizontal position as shown in Fig. 2 and because of the extension arms 7 the frame 16 is materially raised when inverted 5 and lies above the inverted position of the seat frame 7.

As will be noted from the above, the foot frame 10 is carried upon the seat frame 7 and the bed frame 16, both the latter being 10 separately pivoted on the frame 4—5 on the housing structure. As a result its movement and position are controlled by the movement and position of the frames 7 and 16, which are in turn related by their connection to 15 the frame 10. The structure formed by the three frames 7, 10, and 16 is therefore movable about the pivots 9 and 18 and the proportions of the several members are such that at the conclusion of the movement about 20 the pivots the two bed frames 10 and 16 are aligned in horizontal position above the seat frame 7 as shown in Fig. 2. In order to prevent too far a movement of the frames and stabilize them in perfect alignment, a 25 bridge, comprising arms 21 rigidly fixed to the sides of frame 10 and joined by the bar 22 on the under side of the frame 10 is arranged to contact with the upper side of the inverted seat frame. Another effect of this 30 connection as clearly shown in Fig. 2 is that it constitutes the seat frame an extension, rigid against downward pressures, of the outer or foot frame 10. That is, in extended position the inner end of the foot frame 10 is supported through the seat frame 7, upon 35 the pivot 9; and the main frame 16 is supported in horizontal position upon its own pivoted connection 18 and by its pivotal connection 14 with the foot frame 10. The 40 bridge also functions to prevent lateral spreading or collapse of the side members of the main and foot frames.

Forming the rear of the sofa is the frame 24 which is suitably upholstered in front and 45 is connected to the foot frame 10 by pivots 26. The back frame is carried forward in the unfolding movement of the frames and is retained under the end of the foot frame by a link 27, pivoted to the back frame and 50 slotted over a pin 28 on the foot frame.

Means are provided for supporting the outer end of the frames in the extended position. The arms 12 fixed to the seat frame are extended forwardly, in the inverted position of the frame, as shown in Fig. 2. A leg 31 is pivoted on the end of each arm 12, and a link 32 is pivoted to each leg and the outer end of the foot frame. The links 32 thus support the outer end of the foot 60 frame and effect the needful folding of the legs 31 when the frames are turned into the housing structure. It is to be noted that the leg-link-arm structure connecting the outer ends of the foot and seat frames supplements the pivot-and-bridge connections 65

in producing a bed frame of unusual strength and rigidity without sacrifice of light construction. When the frames are extended, the legs automatically position themselves, immediately behind the back 70 frame 24 which hangs free from contact with the floor under the end of the foot frame and in front of the legs and links. Preferably the bottom front edges of the legs are provided with curved arms 33, so that in 75 the folding up movement of the bed, the legs do not tend to catch under the edge of the foot frame. During the folding movement, the back frame rides on the curved arm 33, until at the end of the movement 80 it rests against the end of the leg structure as shown in Fig. 3. To prevent lateral rocking of the leg structure, the legs are preferably connected at their lower ends by a transverse bar 34. 85

In the folded position of the parts the extension arms 12 rest on shoulders 36, fixed on the housing at the rear.

There is a decided advantage in the arrangement for supporting the foot of the 90 bed, just explained. No intermediate legs are needed and inequalities in the floor or floor coverings cause no trouble.

Means are provided for balancing the 95 weight of the frames so that only a small effort is needed to fold or unfold them. An extension arm 37 is pivoted on each side of the main frame 16 and coil springs 38 of suitable strength connect these arms to fittings 39 on the housing structure. The location of the arms 37 and the fittings 39 is such that the springs 38 are under tension in both the folded and extended positions of the frames. Stop pins 40 support and position the arm in the extended position of the bed frame, and in the folded position, the stop pin 41 performs a like function. The purpose of the pivoted arms is to increase the lever-arm on which the springs act in both 100 positions of the bed frame. In the folded position as seen in Fig. 3, the spring tends to initiate the unfolding movement and as seen in Fig. 2 the spring tends to initiate the 105 folding movement of the frames. Preferably a second spring 42 on each side connects the main frame 16 to the cross rail 22. These 110 latter springs are placed under tension during the unfolding movement of the frames and help to counterbalance nearly all of the weight of the unfolding frames. 115

Pivoted to the head end of the main frame is the head frame 43, the pivotal connection forming a knuckle joint 44 as shown in Fig. 5. A link 45 connects the head frame to an arm 46 fixed on the foot frame so that movement of the head frame is harmonized with the movement of the other frames. In the folded position of the parts, the head frame extends vertically 120 downwardly from the end of the main frame 125 and outwardly about the pivot 47 to an inverted horizontal position as shown in Fig. 2. 130

at the front of the housing structure. When the frames are unfolded the head frame is automatically moved into a horizontal position, further downward movement being prevented by the knuckle joint. Fixed on the end of the head frame is a relatively high head board 47. In the folded position of the parts, this head board extends horizontally across the bottom of the housing structure aiding in the retention of the bedding and mattress but in the unfolded position, it forms a panel substantially filling the upper end of the housing, in which position it not only improves the appearance of the structure but also prevents displacement of the pillows and falling of articles over the edge.

A top board 48 is pivoted to the housing structure, and in the folded position of the parts overlies the upper edge of the back frame, foot frame and mattress.

A foot board 49 is attached to the end of the foot frame 10 by L-shaped pieces 51. A spring 52 retains the foot board in upright position on the foot frame as shown in Fig. 2, or holds it resiliently against the mattress 53 to retain the latter in position on the foot frame as shown in Fig. 3. The mattress is secured to the spring fabric 54 carried by the bed frames in any suitable manner and upon folding of the frames the head end of the mattress is doubled against the head board as shown in Fig. 3, the mattress then lying behind the back frame, below the seat and behind the vertically disposed head frame, as shown in Fig. 3. Owing to this disposition of the frames, the mattress may be of full standard thickness which with the spring provides a bed of unusual comfort.

I claim:

1. A sofa bed comprising a housing structure, a main bed frame arranged in said housing structure, a seat frame arranged in said housing structure, a foot frame pivotally connected to both said seat and main frames, a head frame pivotally arranged upon the main frame, a link connecting the head and foot frames, and a leg pivotally connected to the seat and foot frames for supporting the extended frames.

2. A sofa bed comprising a housing structure, a foot frame arranged in said structure in an upright position and adapted to be extended to horizontal position, a back frame pivoted directly to and supported by said foot frame in both positions thereof and a slotted link additionally connecting the foot and back frame.

3. A sofa bed comprising a housing structure, a main bed frame arranged in said housing structure, a foot frame pivotally connected to said main frame and occupying an upright position when folded and a horizontal position when unfolded, a back frame

supported by said foot frame in both positions thereof, a seat frame mounted on pivots fixed respectively on said housing structure and on said foot frame, and a leg pivotally connected to said seat and foot frames for supporting said foot frame in the horizontal position.

4. A sofa bed comprising a housing structure, an invertible seat frame pivoted on said housing structure, a foot frame pivoted to said seat frame, and a bridge across said foot frame to brace the sides thereof and engaging said seat frame to stabilize the two frames when the seat frame is inverted.

5. A sofa bed comprising a housing structure, an invertible seat frame mounted on pivots fixed on said housing structure, a foot frame having fixed pivots journaled in said seat frame, a bridge across said foot frame to brace the sides thereof and engaging said seat frame to stabilize the two frames when the seat frame is inverted, and a leg pivotally connected to said seat and foot frames.

6. A sofa bed comprising a housing structure, an invertible seat frame pivoted on said housing structure, a foot frame pivoted to said seat frame, a bridge across said foot frame to brace the sides thereof and engaging said seat frame to stabilize the two frames when the seat frame is inverted, a back frame pivotally supported solely by said foot frame, and means for positioning said back frame in the folded position of the frames and for retaining said back frame below the foot frame in the extended position of the frames.

7. A sofa bed comprising a housing structure, an invertible seat frame pivoted on said housing structure, a foot frame pivoted to said seat frame, a bridge across said foot frame to brace the sides thereof and engaging said seat frame to stabilize the two frames when the seat frame is inverted, a back frame pivoted to said foot frame, and a leg for supporting the foot frame when extended and for positioning the back frame when the frames are folded.

8. A sofa bed comprising a housing structure, an invertible seat frame pivoted on said housing structure, a foot frame pivoted to said seat frame, means on said foot frame adapted to engage said seat frame to stabilize the two frames when the seat frame is inverted, a back frame pivoted to the foot frame, and a leg for supporting the foot frame and for positioning the back frame.

9. A sofa bed comprising a housing structure, an invertible seat frame pivoted on said housing structure, a foot frame pivoted to said seat frame, means on said foot frame adapted to engage said seat frame to stabilize the two frames when the seat frame is inverted, a back frame pivoted to the foot frame, a leg for supporting the foot frame,

and means on said leg for moving the back housing structure, a foot frame pivoted to frame to position against the end of the leg, said seat frame, means on said foot frame when the parts are folded.

10. A sofa bed comprising a housing structure, an invertible seat frame pivoted on said housing structure, a foot frame pivoted to said seat frame, means on said foot frame adapted to engage said seat frame to stabilize the two frames when the seat is inverted, a main bed frame pivotally connected to said housing structure and to said foot frame, a head frame pivoted to the main frame, and a head board fixed on said head frame and adapted to engage said seat frame to stabilize the two frames when the seat frame is inverted, a main bed frame pivotally connected to said housing structure and to said foot frame, a head frame pivoted to the main frame, and a link connecting said head and foot frames.

15. 11. A sofa bed comprising a housing structure, an invertible seat frame pivoted on said

main bed frame pivotally connected to said housing structure and to said foot frame, a head frame pivoted to the main frame, and a head board fixed on said head frame and in the folded position of said frames extending horizontally across the base of said housing structure to retain the bedding and mattress against the main frame.

In testimony whereof, I have hereunto set my hand.

WILLIAM L. MURPHY.
